UNITED STATES PATENT OFFICE.

WILLIAM W. HALL, OF INDIANAPOLIS, INDIANA.

DESIGN FOR A VEHICLE-SPRING.

SPECIFICATION forming part of Design No. 32,180, dated January 30, 1900.

Application filed January 4, 1900. Serial No. 398. Term of patent 7 years.

To all whom it may concern:

Be it known that I, WILLIAM W. HALL, a citizen of the United States, residing at Indianapolis, in the county of Marion and State of Indiana, have invented and produced a new and original Design for a Vehicle-Spring; and I do hereby declare the following to be a full, clear, and exact description of the invention, such as will enable others skilled in the art to which it appertains to make and use the same.

In the drawings, Figure 1 is a side view of the vehicle-spring. Fig. 2 is a plan view of the same.

As shown in the drawings, the leading or material feature of my design consists of a flat leaf-spring provided with a curved middle portion A, having a semicircular bent por-

tion B at each end, short straight portions C, arranged in alinement with each other and projecting from the portions B toward each other over the end portions of the middle portion A, and semicircular bent portions D, curved upwardly and in the reverse direction from the bent portions B and projecting from the adjacent ends of the straight portions C.

What I claim is—

The design for a vehicle-spring, as herein shown and described.

In testimony whereof I affix my signature in presence of two witnesses.

WILLIAM W. HALL.

Witnesses:

WM. HILD, Jr.,
JOHN G. McCULLOUGH.
